COMBINED POCKET KNIFE AND MONEY CLIP

Clayton A. Laughlin, Minneapolis, Minn., assignor to Arthur Salm Inc., Chicago, Ill.

Original design application Sept. 20, 1968, Ser. No. 13,640, now Patent No. 218,729, dated Sept. 22, 1970. Divided and this application Aug. 7, 1969, Ser. No. 19,342

Term of patent 14 years

Int. Cl. D2—08
U.S. Cl. D2—407

FIG. 1.

FIG. 2.

FIG. 4.

FIG. 5.

FIG. 6.

FIG. 1 is a perspective view of a combined pocket knife and money clip incorporating my new design;

FIG. 2 is a plan view on a reduced scale of the bottom face of the design of FIG. 1;

FIG. 3 is a plan view on a reduced scale of the bottom face of a second embodiment of a combined pocket knife and money clip incorporating my design;

FIG. 4 is a plan view on a reduced scale of the bottom face of a third embodiment of a combined pocket knife and money clip incorporating my new design;

FIG. 5 is a plan view on a reduced scale of the top face of the combined pocket knife and money clip of FIG. 1; and

FIG. 6 is a left side view of the combined pocket knife and money clip of FIG. 1.

This is a division of application Ser. No. D. 13,640 filed Sept. 30, 1968, and now Patent No. D. 218,729.

I claim:

The ornamental design for a combined pocket knife and money clip, substantially as shown and described.
